Attorney

UNITED STATES PATENT OFFICE.

HARRY L. GRANT, OF TAMAQUA, PENNSYLVANIA, ASSIGNOR TO ATLAS POWDER COMPANY, OF WILMINGTON, DELAWARE, A CORPORATION OF DELAWARE.

PROTECTING DEVICE FOR ELECTRIC DETONATORS.

Application filed November 20, 1925. Serial No. 70,368.

This invention relates to a protecting device for electric detonators of the character of that shown in my copending application, Serial No. 748,214, filed on November 6, 1924.

5 Like the device of the application referred to, the protecting device of the present invention is intended to be applied to the lead-in wires of electric detonators and to serve, while in position, to establish a short circuit 10 between the two lead-in wires, so that any stray currents imposed upon the lead-in wires, outwardly of the point of application of said device, may not find their way to the detonator and prematurely explode the same 15 and so that no difference in potential can be created between the lead wires inwardly of the point of application of the device under the influence of accidental or stray currents imposed upon said wires.

20 I am aware of the fact that it has been proposed to short circuit the main firing cable leading from the blasting machine. However, that method is of utility only at the time of use. An important object of the 25 present invention is to provide a structure which will be operative with respect to the individual detonators, at all times between the time of manufacture of the detonator and until the same is actually exploded on 30 the job, the structure being of particular utility during the time that the detonator is being transported and while it is being handled about the work preliminary to the actual connection of its lead wires to the main 35 firing cable.

The present application is directed to the protection of a specific form of short circuiting shunt and method of applying the same to the lead-in wires of the individual blasting caps with its inner end abutting and resting firmly against the terminal end of the usual insulation of the detonators. In the provision of a structure of this character, which is used only once and then thrown 45 away, it is of importance that it be of a simple and inexpensive nature and one adapted to be applied rapidly by automatic machinery. With this end in view, I have devised the shunt shown in the accompanying drawing wherein:

Fig. 1 is a view of the blank from which the shunt is made,

Fig. 2 is a perspective view of the shunt before application, and

Fig. 3 is a side view of a detonator having 55 the shunt applied thereto.

Like numerals designate corresponding parts in all of the figures of the drawing.

Referring to the drawing, 5 designates the conventional electric detonator and 6 and 7 60 designate the usual lead-in wires of said detonator.

In the ordinary use of the detonator the flow of current of sufficient strength past an igniting element 8, which connects the inner 65 ends of the wires 6 and 7, explodes the detonator. The lead-in wires are insulated, as indicated at 9 and 10, for some distance from the detonator and the ends of the lead-in wires are left bare beyond the point where 70 the insulation terminates, to adapt them for ready application to the firing cable, leading from a blasting machine.

The shunt of the present invention comprises a metal strip 11, which is notched 75 from its opposite edges as indicated at 12 and 13 and bent intermediate its ends, as indicated at 14, to bring the two notched portions into spaced but aligned relation, so that the lead wires 6 and 7 may be positioned 80 in these notches. After the wires have been positioned in the notches, pressure is applied to the opposite ends of the shunt and it is forced into intimate and gripping relation to the lead wires, as indicated in Fig. 3. It 85 is manifest that the interlocking of the lead wires in these notches, cut from opposite directions, renders the accidental dislodgement of the shunt from the lead wires, practically 90 impossible. Furthermore, this arrangement 95 aids in maintaining the shunt in position upon the wires during the clamping operation. When it is desired to remove the shunt, preparatory to use of the detonator, the shunt may be stripped longitudinally 100 from the wires. This action of stripping the shunt from the wires aids in cleaning them and, to increase the cleaning and scraping action of the shunt upon the wires, the edges of the slots 12 and 13 are made as 105 sharp as possible. The result is that the wires are rendered bright and clean and put in such condition as to make effective electrical union with the main blasting cable when they are attached thereto. By referring to Fig. 3, it will be seen that the shunt is positioned so that it closely abuts the terminal ends of the insulation upon the lead

wires. Since this insulating material protects the lead wires from the shunt, inwardly, and the shunt itself protects the detonator from the point of its application, outwardly, it is clear that as long as the shunt remains in position, the detonator cannot possibly be exploded by stray currents from any source whatever, because no difference in potential can be created between the lead wires inwardly of the shunt. It is not to be understood that the device is of utility only when actually touching the termination of the insulation. It will give a very appreciable measure of protection even when spaced somewhat from the insulation because the influences which might bring about such difference in potential between the lead wires as to explode the detonator, are not those sought to be created by an intelligent human agency but only those which might accidentally occur. Stray currents of such low E. M. F. as to escape ordinary notice constitute a marked source of danger and are rendered absolutely harmless by this invention.

It is to be understood that the invention is not limited to the precise construction set forth but that it includes within its purview whatever changes fairly come within either the terms or the spirit of the appended claims.

Having described my invention, what I claim is:

1. The herein described method of applying a shunt to an electric detonator, which consists of notching a strip of conductive material in opposite directions from its opposite edges, bending said material upon itself to bring said notches into substantial alignment, passing the bared portions of the

lead wires through said notches and compressing the material of the strip into firm engagement with the lead wires.

2. The herein described method of applying a shunt to an electric detonator, which consists of notching a piece of conductive material from its opposite edges, bending said conductive material upon itself, inserting the lead wires of the detonator in said notched portions and then clamping the shunt into firm engagement with said wires by forcing the bent portions of said strip toward each other.

3. A shunt of the character described comprising a flat strip of conductive material notched from its opposite edges and bent upon itself, to bring its notched portions into alignment with each other in such manner that wires to be united may be threaded through said notched portions.

4. A shunt of the character described comprising a piece of flat sheet metal notched from its opposite edges, bent upon itself and compressed into firm engagement with the lead wires of a detonator, which lead wires pass through said notched portions.

5. The combination with an electric detonator, the lead wires of which are covered with insulating material for a portion of their length and are bare for the remainder of their length, of a shunt comprising a flat piece of metal slotted from its opposite edges and bent upon itself, said wires passing through said slotted portions and the material of the shunt being forcibly pressed into engagement with said wires, by bending its free ends toward each other.

In testimony whereof he affixes his signature.

HARRY L. GRANT.
